UNITED STATES PATENT OFFICE.

BENJAMIN F. SHEIBLEY AND WILHELM MOLLER, OF LEWISTOWN, PENNSYLVANIA.

CUT-OUT ATTACHMENT FOR INTERNAL-COMBUSTION ENGINES.

No. 922,528.

Specification of Letters Patent. Patented May 25, 1909.

Application filed April 25, 1908. Serial No. 429,195.

To all whom it may concern:

Be it known that we, BENJAMIN F. SHEIBLEY and WILHELM MOLLER, citizen of the United States and subject of the King of Denmark, respectively, residing at Lewistown, in the county of Mifflin and State of Pennsylvania, have invented certain new and useful Improvements in Cut-Out Attachments for Internal-Combustion Engines; and we do declare the following to be a full, clear, and exact description of the invention, such as will enable others skilled in the art to which it appertains to make and use the same, reference being had to the accompanying drawings, and to the figures of reference marked thereon, which form a part of this specification.

Our invention relates to internal combustion engines and has for its object to provide a cut out device or attachment therefor for the purpose of simultaneously cutting out the combustible gas from the cylinders and breaking the electric circuit, thus cutting out the ignition.

In the operation of motor vehicles it frequently becomes necessary to suddenly cut out the engine, as for instance when coming upon a rut or obstacle in the road or whenever occasion requires it. In cutting out the engine under the usual conditions the same is accomplished generally by cutting out the spark and by throttling the carbureter. The engine, however, continues to turn over and if the carbureter is throttled a certain amount of combustible mixture is carried into the cylinders and consequently wasted; or if the carbureter is throttled to too great an extent it acts as a break upon the engine choking the same. When the engine is cut out or slowed down by delaying the spark and throttling the carbureter the electric current is being consumed as well as the combustible mixture.

As will appear from the following description an internal combustion engine having our attachment can be instantly cut out without interfering in any way with the commutator or timer and without throttling the mixture, thus instantly cutting out the ignition and causing the engine to cease to take into its cylinders any combustible mixture, thus saving the electric current and economizing on the fuel.

Our invention therefore has for its object to provide a cut out device or attachment for internal combustion engines; which by

the operation of a single lever or other suitable means for conveying motion, the ignition is cut out and the combustible mixture is prevented from entering the engine cylinders simultaneously. The advantages of this attachment aside from the fact that it furnishes instant control over the engine and economizing in electric current and fuel is that it allows the cylinders to take in a quantity of cool atmospheric air, thereby greatly facilitating the cooling of the cylinders, and allows the pistons to perform a number of strokes thus enabling the same to carry a quantity of lubricating oil over the walls of the cylinder, for the reason that as soon as the ignition of the combustible mixture ceases, the extreme heat caused thereby and which burns the oil from the walls of the cylinders ceases, allowing the walls of the cylinders to again become coated with oil which is carried up by the pistons.

A further object of our invention is to provide a cut out device or attachment for internal combustion engines which can be quickly and easily applied to all existing types of engines whether of the two or four stroke type, and without altering the engine or interfering with its regular operation in the slightest degree.

A further object of our invention is to provide a cut out device or attachment for internal combustion engines which is extremely simple in its construction and which can be applied to an engine in a short period of time by any ordinary mechanic. No special tools or implements or particular knowledge of the engine is required in order to effectually equip an engine with the device.

With these objects in view our invention consists in the novel construction and arrangement of parts of the attachment; and our invention consists in the arrangement of the valve and the circuit breaker operated thereby.

Our invention also consists in providing a valve and circuit breaker between the carbureter or mixing device and the intake valves or intake port of an internal combustion engine.

Our invention also consists in certain other novel details of construction and in certain combinations of parts all of which will be fully described and afterward specifically pointed out in the appended claims.

Referring to the accompanying drawings:

Figure 1 is an elevation of an internal combustion engine of usual type showing our cut out attachment applied thereto. Fig. 2 is a front elevation of an internal combustion engine of usual type showing our cut out attachment applied thereto. Fig. 3 is a longitudinal sectional view through the cut out attachment. Fig. 4 is a side elevation of the attachment showing valve open and 10 circuit broken, and Fig. 5 is a front elevation of the attachment.

Like numerals of reference indicate the same parts throughout the several figures in which—

15 1 indicates an internal combustion engine of any type or construction, and 2 indicates the cut out attachment.
4 indicates the intake pipe, which, as shown in Figs. 1 and 2, is secured to the engine near the top thereof and communicating with the intake manifold of the engine, and 5 indicates a carbureter or mixing device of any design or construction. It will be seen from Figs. 1 and 2 that the attachment 2 is applied to the intake pipe 4 at a point between the carbureter or mixing device 5 and the intake manifold of the engine, and the attachment is preferably applied as near as possible to the intake manifold and 30 intake valves.

Referring now to Fig. 3 it will be seen that the attachment 2 comprises a short cylinder 6 having one end 7 threaded and a hex nut 8 formed thereon, said hex nut 8 providing a shoulder 9 as shown. Arranged within the cylinder 6 near the outer end thereof is a guide 10 through which the valve stem 11 of the valve 12 passes. A coil spring 13 bearing against the guide 10 and carried on the valve stem 11 is provided for normally seating the valve 12 in a seat 14 formed on the outer end of the cylinder 6.

Secured over the outer end of the cylinder as shown in Fig. 4 is a bracket 15, said 45 bracket being provided with two arms 16 and 17 which are preferably secured to the cylinder 6 by means of screws 18. The bracket 15 is provided with an opening 19 through which the valve stem 11 passes, and 50 carried on said bracket 15 is the circuit breaker 20. Said circuit breaker 20, as shown in Fig. 3, comprises a plunger 21 and plunger stem 22, said plunger and stem being accommodated in a small shell or cylinder 23, and the outer end of said cylinder 23 is provided with a plug 24 of insulating material, said plug 24 having a flange 25 thereon extending over the end of the shell or cylinder 23 covering the same, as clearly shown 55 in Fig. 3. Threaded on the plug 24 or otherwise suitably secured thereon is a small metallic band 26 by means of which the wire 27 is secured to the circuit breaker. The 60 plug 24 is provided with a central opening through which the plunger stem 22 passes,

and the outer end of said stem is provided with a small bar 28 at right angles to the stem 22, a coil spring 29 being arranged within the cylinder 23 and between the plunger 21 and the insulating plug 24, said 70 spring normally holding the plunger 21 in position shown in Fig. 3 and the bar 28 in contact with the metallic band 26.

A binding post 30 is provided on the bracket 15 to which the wire 27 is secured 75 and to which the ground wire 31 of the circuit is also secured.

Having thus described the several parts of our invention its operation is as follows: The attachment being provided on an internal combustion engine at any convenient place between the carbureter or mixing device 5 and the intake valves or intake ports of the engine; as shown in Fig. 3 an operating cord 32 is secured to the outer end of 80 the valve stem 11, said cord leading to a suitable lever or other device within easy reach of the operator of the machine in such manner that the valve 12 can be quickly unseated by the operating cord 32. When the 85 operating cord 32 is pulled the valve 12 is opened against the pressure of the coil spring 13 on the valve stem 11 which movement of the valve 12 moves the plunger 21 of the circuit breaker carrying the bar 28 90 on the end of the plunger stem 22 out of contact with the metallic band 26 on the outer end of the circuit breaker. As the ground wire passes to the binding post 30 and said post is connected with the metallic band 26 100 on the circuit breaker by means of the wire 27 the current is grounded through the metallic band 26, cross-bar 28, plunger stem 22, plunger 21, cylinder 23, bracket 15 and cylinder 6 of the attachment. As soon, therefore, as the valve 12 is raised in the position shown in Fig. 4 the bar 28 on the plunger stem 22 is carried out of contact with the metallic band 26, thus breaking the circuit 105 as the binding post 30 is insulated from the bracket 15 as clearly shown in Fig. 3. The result is that communication between the engine cylinder and the atmosphere is effected at a point between the carbureter or mixing device 5 and the intake valves or 110 intake ports of the engine. As the pistons therefore perform their suction stroke atmospheric air is drawn into the cylinders through the attachment instead of through the carbureter or mixing device 5. This charge of atmospheric air into the cylinders is not combustible and therefore there is nothing within the engine cylinders to ignite, but in order to absolutely insure an instant cut out of the engine the circuit 115 breaker is simultaneously operated by the valve 12, thus breaking the circuit and cutting out the ignition. The engine of course continues to turn over for a number of revolutions during which time no combustible 120

125 breaker is simultaneously operated by the valve 12, thus breaking the circuit and cutting out the ignition. The engine of course continues to turn over for a number of revolutions during which time no combustible 130

- 5 mixture is being drawn into the cylinders, and the circuit being broken the electric current is being saved which allows the batteries or source of energy to recuperate as is of course clearly evident. When it is desired to allow the engine to again take up its revolutions regularly the valve 12 is seated as shown in Fig. 3 which instantly cuts out the atmospheric air from the cylinders causing the cylinders to take their 10 charges of combustible mixture through the carbureter or mixing device 5 simultaneously closing the electric circuit thus cutting in the ignition.
- 15 A further advantage of the application of our device to an internal combustion engine is that in the event of derangement of the intake valves or by reason of an improper seating any back firing of the combustible 20 gases which might occur, passes out into the atmosphere through the valve 12, thus relieving the carbureter or mixing device of this pressure which is frequently so great as to disrupt and demolish the carbureter or 25 mixing device. The normal action of the engine pistons drawing the combustible mixture into the engine cylinders tends to seat the valve 12 and maintain same in a seated position, the coil spring 13 on the valve stem 30 11 only being of such tension as to insure the proper seating of the valve while the engine is at rest or in starting. A slight pressure therefore within the intake manifold or within the intake pipe 4 between the 35 intake valves or ports and the carbureter or mixing device 5 will instantly unseat the valve 12 and relieve the pressure, thus insuring the carbureter or mixing device against any back pressure caused by back-firing.
- 40 As will appear from the foregoing description the location of the attachment on an internal combustion engine is entirely immaterial so long as the same is applied at a point between the carbureter or mixing 45 device 5 and the intake valves or ports, although it is preferable to locate the same at a point as close as possible to the intake valves or ports as clearly shown in Figs. 1 and 2.
- 50 Having thus fully described our invention what we claim as new and desire to secure by Letters Patent of the United States, is:—
1. A cut out attachment for internal combustion engines comprising a cylinder having means thereon for attachment to an 55 internal combustion engine, a valve seat on said cylinder, a valve and valve stem, a spring on said valve stem for holding said valve seated, said valve stem being arranged for connection with means for raising said valve from its seat, a bracket carried on said cylinder and a circuit breaker carried on said bracket, said circuit breaker comprising a plunger, a cylinder accommodating said plunger and a plunger stem, a contact thereon, said plunger being arranged in the path of movement of the said valve in such manner that upon unseating of the said valve the said plunger is engaged and moved, thereby moving the said contact on the plunger stem thus breaking the ignition circuit. 60
2. A cut out attachment for internal combustion engines comprising a cylinder having means thereon for connection with an internal combustion engine, a valve seat on said cylinder and a valve for said seat, a circuit breaker associated with said valve, said circuit breaker comprising a plunger and an electrical contact, the whole being arranged in such manner that upon the unseating of the said valve the said plunger is engaged by the said valve to break the ignition circuit. 65
3. An attachment for internal combustion engines comprising a valve, a valve seat, a circuit breaker associated with said valve, said circuit breaker comprising a plunger located in the path of said valve and arranged to be engaged by said valve upon the unseating thereof to move said plunger and break the ignition circuit. 70
4. An attachment for internal combustion engines comprising a valve and valve seat adapted to be placed upon an internal combustion engine at a point between the carbureter or mixing device and the engine cylinder, a circuit breaker associated with said valve, said circuit breaker comprising a plunger and an electrical contact, said plunger being located in the path of movement of said valve and arranged to be moved by said valve upon the unseating thereof, the whole arranged in such manner that upon the unseating of said valve communication is effected between the engine cylinder and the atmosphere and the said plunger is moved to break the ignition circuit. 75
